ELECTRIC BREAD TOASTER

Pierre Leon Decrouez, Ridley Township, Delaware County, Pa., assignor to Proctor-Silex Incorporated, Philadelphia, Pa., a corporation of New York

Filed Feb. 8, 1968, Ser. No. 10,506

Term of patent 14 years

Int. Cl. D7—04

U.S. Cl. D81—10

FIG. 2

FIGURE 1 is a front isometric view of an electric bread toaster embodying my new design; and

FIGURE 2 is a rear isometric view of the same.

The dominant features of my design reside in the portions shown in full lines.

The wood grain is shown on the ends to indicate a contrast in material, texture, and color rather than indicating any specific pattern or texture.

I claim:

The ornamental design for an electric bread toaster, as shown and described.
